UNITED STATES PATENT OFFICE.

LEONHARD B. LOTZ, OF PLAQUEMINE, LOUISIANA.

CANE-LOADER.

SPECIFICATION forming part of Letters Patent No. 731,923, dated June 23, 1903.

Application filed February 18, 1903. Serial No. 143,982. (No model.)

To all whom it may concern:

Be it known that I, LEONHARD B. LOTZ, a citizen of the United States, and a resident of Plaquemine, in the parish of Iberville and State of Louisiana, have invented certain new and useful Improvements in Cane-Loaders, of which the following is a specification.

My invention is an improvement in cane-loaders, being in the nature of a loading device specially designed for use in loading sugar-cane on wagons or other carriers; and the invention consists in certain novel constructions and combinations of parts, as will be hereinafter described and claimed.

15 In the drawings, Figure 1 is an elevation of my improved loader as in use. Fig. 1^a is a detail side elevation; and Fig. 2 is a detail plan view of the base, showing the triangular form thereof.

20 In carrying out my invention I provide a suitable base A, which may preferably be triangular in form and is mounted on a broad-gage carriage, so as to give sufficient width at the base to properly support the

25 loading devices. This base is provided with a foot-bearing A' for the lower end of the shaft B, which shaft journals at its upper end in bearings at C' and D' in plates C and D. The plate C is arranged a short distance be-

30 low the plate D, and the loader is arranged at about the upper end of the shaft B, the two plates forming a comparatively broad bearing for the upper end of the shaft B in the use of the apparatus. The plate C is braced

35 by three strut-braces E, F, and G, secured at their lower ends at E', F', and G' to the base A and secured at their upper ends, usually by nuts, above and below the plate C to the said plate, as shown. The brace-rod G ex-

40 tends through and beyond the plate C and up to and connects with the plate D, nuts being provided at G² and G³ below and above the plate C, and the extension g of the rod G, extending from the plate C, is secured near

45 its upper end to the plate D, as shown in Fig. 1. A horizontally-extending arm or beam H is secured at its inner end to the shaft B at a point slightly below the plate C and extends outwardly sufficiently far to project

50 beyond the sides of the base A to such extent as to deliver the cane or other material being handled into a wagon alongside the

base A and is provided at its outer end with the upturned branch H', from the upper end of which extends a guy-line I, which connects 55 at its inner end with a pin J, projecting out of the shaft B through the top plate D. This guy-line helps support the arm H, and said arm is also supported by a strut-brace K, secured at its lower end to the shaft B and at 60 its upper end to the arm H, at a short distance from the outer end of the said arm H, leaving a portion h between the branch H' and the connection K' of the strut-brace K, upon which operates the roller or trolley L, from 65 which the grab-hooks or tongs are suspended, as shown. This travel of the grab-hook back and forth permits the adjustment of the grab-hooks or tongs to properly take up and deliver cane at different points. A cross- 70 brace M extends from the strut K, at about the middle thereof, horizontally inward and connects with the shaft B, supporting the strut, as shown, and its cross-brace connects near its outer end by a rod M' with the arm 75 or beam H about midway between the connection K' and the shaft B, as shown. The shaft B is provided with a handle N, by which it may be turned to adjust the hooks or tongs to position to deliver the cane, as shown, or 80 they may be operated to secure the load of cane to be delivered to the wagon, as will be understood from Fig. 1. A suitable pulley-block is suspended from or carried by the pulley L, and a rope O, extending through guides 85 O' and O² on the base A, may be hitched to a mule or other power for raising the tongs. The tongs are suspended from the pulley-blocks and may be provided with means for tripping them in order to secure a discharge 90 of the load whenever desired.

The special form of grab-hook shown constitutes the subject-matter of a separate application for patent executed by me of even date herewith.

In Fig. 1 I show a guy-line P, which connects by a hook or otherwise with the upper plate D and by an eyebolt P' with the tongue, as shown in Fig. 2.

The apparatus may be used for loading 100 sugar-cane or other crops. In loading sugar-cane, the cane having been cut as usual and thrown or corded four rows in one, thus leaving two clear rows for the loader to move in,

the loader drawn by horses or mules is moved along the row or pile of cane. The open grab-hook being lowered over the cane and so placed as to grab up an armful is operated 5 by means of the hoisting-rope O to raise the cane clear of the ground, when by means of the handle N the operator can turn the bundle of cane held by the grab-hook around to a point over the wagon, when the tongs or 10 hooks can be tripped to deliver the cane to the wagon, as desired.

Having thus described my invention, what I claim as new, and desire to secure by Letters Patent, is—

- 15 1. A cane-loader substantially as herein described, comprising the base, the upright shaft journaled at its lower end to the base, a plate C having a bearing for the shaft and openings for the braces, the braces secured 20 at their lower ends to the base and at their upper ends to the plate C, one of the said braces being extended beyond the said plate C, a plate D secured to such extension of the brace and having a bearing for the upright shaft, 25 a lateral arm secured to the shaft at a point below the plate C and provided at its outer end with an upturned wing or branch, a guy-line extending from this wing or branch, and connected at its inner end with the shaft, a 30 strut-brace between the shaft and arm or beam and connected with the latter at a short distance from the upturned branch or wing |

thereof, a roller or trolley operating on the arm or beam between its upturned wing and the strut-brace and means whereby the shaft 35 may be turned, substantially as set forth.

2. The combination with the base having a bearing for the lower end of the shaft and the shaft journaled at its lower end in said bearing, of the plates C and D having bearings for the shaft near the upper end thereof, and the lateral arm or beam on the shaft near its upper end, and the braces secured at their lower ends to the base and at their upper ends to the plate C and one of said braces 40 45 being extended above the plate C and connected with the plate D, substantially as set forth.

3. The combination of the shaft B having a lateral arm or beam provided at its outer end with an upturned arm or wing, a strut-brace secured at its lower end to the shaft and at its upper end to the arm or beam at a point in front of the upturned wing thereof, and the hoisting devices movable on the arm or 50 beam between the upturned wing thereof and the upper end of the strut-brace, and limited in its movement thereby, substantially as set forth.

LEONHARD B. LOTZ.
